UNITED STATES PATENT OFFICE.

ALBERT O. BUCKIUS, JR., OF CHICAGO, ILLINOIS, ASSIGNOR TO THE NATIONAL MALLEABLE CASTINGS COMPANY, OF CLEVELAND, OHIO, A CORPORATION OF CALIFORNIA.

JOURNAL-BOX-SECURING MECHANISM.

1,023,809.

Specification of Letters Patent. Patented Apr. 23, 1912.

Application filed January 8, 1912. Serial No. 670,008.

To all whom it may concern:

Be it known that I, ALBERT O. BUCKIUS, Jr., of Chicago, Cook county, Illinois, have invented a new and useful Improvement in 5 Journal-Box-Securing Mechanism, of which the following is a full, clear, and exact description, reference being had to the accompanying drawings, forming part of this specification, in which—

10 Figure 1 is a side elevation showing a portion of a truck side frame and journal box provided with my improved fastening device; and Fig. 2 is a longitudinal vertical section of the journal box.

15 My invention relates to the securing of journal boxes to side frames by retainers of the general form shown in the patent to J. J. Byers, No. 996,000, dated June 20th, 1911. In the structure shown in that patent, the bolt is threaded through an eye or holder at the bottom of the journal box.

20 With such holders, it will be necessary, in removing the journal box, to jack up the side frame until the upper end of the securing device is below the ledge of the side frame over the journal box. As this distance is several inches, the device of said 25 invention is designed to overcome this difficulty and reduce the requisite amount of jacking up in order to remove the journal box or insert a new one.

To that end, the invention consists in providing the journal box with a retainer 30 having a side opening through which the securing device may be inserted without threading the same endwise through the retainer.

The invention also consists in arranging 35 a recess for the head of the bolt or securing device, which is open at the side and bottom and will allow the head to be moved upwardly within the recess after the retaining device has been moved sidewise into 40 the retainer of the journal box.

In the drawings, 2 represents a portion 45 of the side frame of a car truck, having at the end an overhung extension 3 to receive and rest on the journal box 4. The lower 50 face of this projection is preferably horizontal to fit the top of the box, and the end of the side frame has a vertical bearing face 6 at substantially right angles to the bearing face 5, the box fitting in the angle 55 between these two faces.

7 is the strap bolt, forming the securing means, this bolt extending downwardly through the end of the overhung extension around and underneath the box, and having at its lower end a head 8 to enter a recess 60 in the side frame. The upper end of the bolt is threaded at 9 to receive a holding nut 10.

11 is a retainer, which is preferably cast integral with the box, and is of hook-like 65 form, being open at one side, so that the lower horizontal portion of the bolt or securing device may be swung into this retainer. The box is preferably grooved around its intermediate and lower portions 70 to receive the securing bolt, this groove 12 projecting inwardly from the outer surface of the box, as shown in Fig. 2. The overhanging ledge portion 3 of the side frame is preferably provided with a depending 75 lip or rib 3^a at its outer end, which forms between it and the inner vertical bearing face a recess to receive the upper part of the box. This relieves the bolt from any 80 shearing strain.

The portion of the side frame having the vertical bearing face is provided with a recess 13; preferably cast therein, this recess being open at the bottom and side, and being of sufficient size to receive the head 85 of the securing bolt and of sufficient height to allow the bolt to be pushed up and drawn tight when the box is in position.

In assembling the parts, the box is put 90 in place, the securing bolt is pushed up through the hole in the overhanging ledge, and its horizontal portion is then swung around into the retainer, its head then being beneath or partially within the receiving recess. The bolt is then pushed up into the 95 groove in the box, its head moving up within the receiving recess, and the nut is then tightened to hold the box securely in place.

If the nut works off or becomes loose, the 100 securing bolt can only drop down until it strikes on the retainer hook, which prevents it from dropping out, as the head at this time cannot move sidewise from the receiving recess. If the depending lip or rib on 105 the overhang of the side frame is one inch in depth, and the retainer opening is one inch in depth, then the head of the bolt will move up substantially two inches within the 110 recess and can only drop an inch if the nut

is loosened or lost. Consequently, the bolt will still hold the box in place, even if the nut is lost off from it.

The advantages of my invention result from the fact that the parts may be assembled and secured in place, and may also be removed and replaced without excessive jacking up of the side frame. The side frame only needs to be jacked up until the upper end of the box drops below the rib of the overhang, when the bolt can then be dropped down onto the retaining hook and swung out to release the box.

Many changes may be made in the form and arrangement of the box, the side frame, the securing device, the retainer, &c., without departing from my invention.

I claim:—

1. A journal box for car axles, having a retainer at its lower portion provided with a side opening to receive a securing device, said retainer being arranged to prevent dropping away of the securing device; substantially as described.
2. A journal box for car axles, having a groove or recess to receive a securing device, said box having in its lower portion a retainer open at the side to receive the securing device, said retainer being arranged to prevent dropping away of said securing device; substantially as described.
3. A journal box for car axles having formed as a part thereof a retainer to receive a securing device, said retainer having a lateral opening to allow admission of the securing device without threading, said retainer being arranged to prevent dropping away of the securing device; substantially as described.

4. In a car truck, a side frame having a seat for a journal box opened at the bottom and side, a journal box having a retainer with a lateral opening, and a securing bolt or strap extending through the retainer and securing the box to the side frame; substantially as described.

5. In a car truck, a side frame having a seat for a journal box opened at the bottom and side, a journal box having a retainer with a lateral opening, and a securing bolt or strap extending through the retainer and securing the box to the side frame, said strap or bolt having a head within an upwardly extending recess in the side frame; substantially as described.

6. In a car truck, a side frame having an overhung end portion open at the side and bottom, a journal box seated in the opening and having a laterally open retainer, and a securing bolt extending through the retainer and having a head positioned in a recess or side frame, said recess extending upwardly above the opening in the retainer; substantially as described.

7. In a car truck, a side frame having an overhang portion with a depending rib, a journal box seated in the recess inside the rib and having a retainer with a lateral opening, and a securing bolt or strap extending through the retainer; substantially as described.

In testimony whereof, I have hereunto set my hand.

ALBERT O. BUCKIUS, JR.

Correction in Letters Patent No. 1,023,809.

It is hereby certified that the name of the State of incorporation of the assignee in Letters Patent No. 1,023,809, granted April 23, 1912, upon the application of Albert O. Buckius, Jr., of Chicago, Illinois, for an improvement in "Journal-Box-Securing Mechanism," was erroneously written and printed as "California", whereas it should have been written and printed as *Ohio*; and that the said Letters Patent should be read with this correction therein that the same may conform to the record of the case in the Patent Office.

Signed and sealed this 28th day of May, A. D., 1912.

Acting Commissioner of Patents.

is loosened or lost. Consequently, the bolt will still hold the box in place, even if the nut is lost off from it.

The advantages of my invention result from the fact that the parts may be assembled and secured in place, and may also be removed and replaced without excessive jacking up of the side frame. The side frame only needs to be jacked up until the upper end of the box drops below the rib of the overhang, when the bolt can then be dropped down onto the retaining hook and swung out to release the box.

Many changes may be made in the form and arrangement of the box, the side frame, the securing device, the retainer, &c., without departing from my invention.

I claim:—

1. A journal box for car axles, having a retainer at its lower portion provided with a side opening to receive a securing device, said retainer being arranged to prevent dropping away of the securing device; substantially as described.
2. A journal box for car axles, having a groove or recess to receive a securing device, said box having in its lower portion a retainer open at the side to receive the securing device, said retainer being arranged to prevent dropping away of said securing device; substantially as described.
3. A journal box for car axles having formed as a part thereof a retainer to receive a securing device, said retainer having a lateral opening to allow admission of the securing device without threading, said retainer being arranged to prevent dropping away of the securing device; substantially as described.

4. In a car truck, a side frame having a seat for a journal box opened at the bottom and side, a journal box having a retainer with a lateral opening, and a securing bolt or strap extending through the retainer and securing the box to the side frame; substantially as described.

5. In a car truck, a side frame having a seat for a journal box opened at the bottom and side, a journal box having a retainer with a lateral opening, and a securing bolt or strap extending through the retainer and securing the box to the side frame, said strap or bolt having a head within an upwardly extending recess in the side frame; substantially as described.

6. In a car truck, a side frame having an overhung end portion open at the side and bottom, a journal box seated in the opening and having a laterally open retainer, and a securing bolt extending through the retainer and having a head positioned in a recess or side frame, said recess extending upwardly above the opening in the retainer; substantially as described.

7. In a car truck, a side frame having an overhang portion with a depending rib, a journal box seated in the recess inside the rib and having a retainer with a lateral opening, and a securing bolt or strap extending through the retainer; substantially as described.

In testimony whereof, I have hereunto set my hand.
